Term of patent 14 years

(Cl. D26—5)

FIG. 1

FIG. 2

FIG. 3

FIG. 1 is a front perspective view of a data storage unit showing our new design, the rear being substantially plain and unornamented;

FIG. 2 is a top view thereof; and

FIG. 3 is a side view thereof.

The characteristic feature of our design resides in the appearance and arrangement of the several panels forming the front thereof as best shown in FIG. 1.

We claim:

The ornamental design for a data storage unit, as shown and described.
